United States Patent Office.

LOT BONINE, OF VANDALIA, MICHIGAN, ASSIGNOR TO HIMSELF AND
WARREN W. CAMP, OF SAME PLACE.

Letters Patent No. 106,111, dated August 9, 1870.

IMPROVED HAME-CAP FOR HARNESS.

The Schedule referred to in these Letters Patent and making part of the same.

To whom it may concern:

Be it known that I, LOT BONINE, of Vandalia, in the county of Cass and State of Michigan, have invented a new and useful Improvement in Hame-Caps for Harnesses; and I do declare that the following is a true and accurate description thereof, reference being had to the accompanying drawing and to the letters of reference marked thereon and being a part of this specification.

The nature of this invention relates to the construction and securing of a cap or housing, to prevent the water from running down the horse's neck, and to hold the hames in place, so they will not rack against the horse's shoulders and gall them.

The invention consists in a wood or metallic cap, with slots in each end to embrace the hames and hold them in place, and in the peculiar arrangement for securing the cap to the hames.

In the accompanying drawing—

A represents my cap, made of wood or metal, as is most desirable, with its sides turned up slightly, to compel the water to run off.

At its two ends this cap is slotted, to embrace the upper end of the hames B, as shown in the drawing.

The end of the cap is secured to one of the hames by means of a pin, b.

To the other hame a link, c, is secured, into which is hooked a metallic strap, e, bent into a curve at one end, and having a series of slots, longitudinally arranged, near its free end.

This strap passes over the top of the cap, to which it is secured by a button, d, attached to said cap, and passing up through one of the slots in said strap.

There may be a series of holes through the hame, through which the pin passes to secure the cap, so that it may be adjusted for a longer or shorter hame.

The ends of the cap should be extended far enough to carry the water off the horse's neck and the collar.

I am aware that metallic and leather caps have been and are now in use, but they differ widely from my device. I do not claim them or any part thereof; but

What I claim as my invention, and desire to secure by Letters Patent, is—

1. A collar-cap or lionsing, A, slotted at each end to receive and steady the hames, with edges curled upward to compel the water to run off at the sides, and with ends projecting far enough beyond the hames and collar to prevent the water from running into them, substantially as herein described.

2. The means employed to secure the cap to the hames, consisting of the links c, the strap e, the button d, and pin b, when constructed, arranged, and operating substantially as and for the purpose set forth.

LOT BONINE.
